US0D1018229S

(12) **United States Design Patent** (10) **Patent No.:** **US D1,018,229 S**
(45) **Date of Patent:** **** Mar. 19, 2024**

(54) **BATTERY POWERED WRENCH**

(71) Applicant: **William L. Hobson, Jr.**, Philadelphia, PA (US)

(72) Inventor: **William L. Hobson, Jr.**, Philadelphia, PA (US)

(**) Term: **15 Years**

(21) Appl. No.: **29/811,859**

(22) Filed: **Oct. 18, 2021**

(51) **LOC (14) Cl.** **08-05**

(52) **U.S. Cl.**

USPC **D8/22; D8/61**

(58) **Field of Classification Search**

USPC ... D8/17, 21, 22, 23, 24, 25, 26, 27, 28, 29, D8/61

CPC ... B25B 13/06; B25B 13/0035; B25B 13/005; B25B 13/065; B25B 13/46; B25B 13/48; B25B 13/5091; B25B 19/00; B25B 21/004; B60B 29/003; B60B 29/007; B25G 1/066

(57) **CLAIM**

The ornamental design for the battery powered wrench, as shown and described.

DESCRIPTION

FIG. 1 is a perspective front view of the battery powered wrench of the present invention.

FIG. 2 is another perspective front view of the battery powered wrench of the present invention.

FIG. 3 is the front view of the battery powered wrench of the present invention.

FIG. 4 is the rear view of the battery powered wrench of the present invention.

FIG. 5 is an elevation view of the battery powered wrench of the present invention,

FIG. 6 is the opposite elevation view of the battery powered wrench of the present invention.

FIG. 7 is the top view of the battery powered wrench of the present invention; and,

FIG. 8 is the bottom view of the battery powered wrench of the present invention.

1 Claim, 6 Drawing Sheets
